UNITED STATES PATENT OFFICE.

FREDERICK WILLSON, OF READING, PENNSYLVANIA, ASSIGNOR TO T. A. WILLSON & CO., INC., OF READING, PENNSYLVANIA, A CORPORATION OF PENNSYLVANIA.

GOGGLES.

1,254,296.

Specification of Letters Patent. Patented Jan. 22, 1918.

Application filed August 3, 1917. Serial No. 184,209.

To all whom it may concern:

Be it known that I, FREDERICK WILLSON, a citizen of the United States, residing at Reading, in the county of Berks and State of Pennsylvania, have invented certain new and useful Improvements in Goggles, of which the following is a specification.

My invention relates particularly to goggles adapted for industrial uses, such as welding operations which require the employment of windowed eye-cups formed to approximately fit the face. It consists in improved means for securing proper ventilation of the cups in connection with effective exclusion of objectionable light, for advantageously securing the window disk or lens in the front of the cup, and for properly supporting flexibly connected cups when in service; as specifically set forth in connection with the accompanying drawing and defined in the subjoined claims.

Figure 1 is a front elevation of a pair of goggles embodying my invention in preferred form; a portion of one eye-cup being shown in section on the line 1—1 of Fig. 2.

Fig. 2 is a top view partly in longitudinal section on the line 2—2 of Fig. 1.

Fig. 3 is a separate view of a baffle-plate device of modified form; and Fig. 4 shows a lens-retaining ring.

The goggles shown comprise a pair of windowed eye-cups formed with slotted lugs 2, 2 for a flexible bridge connection 2^a, and similar outer lugs 3, 3 for retaining head band 3^a. Each cup is of molded form, shaped to receive an approximately triangular drop-eye disk 4, and with a corresponding eye-inclosing wall having an outer portion 5 extending templeward, an upper portion 6 running along the eyebrow, and lower portions 7 and 8 converging below the eye. Upon the inner inclined wall portion 8 of each cup is formed a transversely rounded rib or circumferential bulge 10 adapted to fit against the respective sides of the nose so as to coöperate with the bridge connection 2^a in satisfactorily supporting the goggle in properly adjusted position.

The lens or light disk 4 is formed with a beveled edge 4^a, and is adapted to be inserted from the inner side of the cup so as to rest marginally upon an annular flange 12 of the latter, with the bevel of the lens extending inward. The cup is formed with an interior 55 annular recess 13 between said flange 12 and

an overhanging inclined-offset portion 14; which recess is adapted to receive a spring retaining ring 15 engaging between said inclined offset 14 and the beveled edge of the inserted lens so as to removably secure the 60 latter against said flange 12.

The wall of each cup is provided with a ventilating opening 20, which is adapted to receive a removably secured baffle-plate device arranged to satisfactorily provide ventilation while at the same time properly obstructing the admission of unintended light or flying matter to the cup. This separately formed device, as shown, comprises a hollow shank portion 21 insertible in the opening 20 as limited by a stop or shoulder 22, and provided with a lateral air inlet or inlets 23 to the cup; and a baffle-plate cap portion 24 larger than the opening and spaced away from the cup-wall, so as to permit passage 70 of air between the wall and the plate through the openings 23, while at the same time serving as an effective baffle. The inserted device may be conveniently secured in position by means of a groove-engaged spring ring 80 25 as indicated. The baffle-plate 24 is preferably arranged approximately in the plane of the eyes and at the widened portion of the triangular cup, and is curved to parallel the adjacent inner wall of the latter. In the 85 modified construction indicated in Fig. 3, however, a flat baffle plate 24^a is shown adapted to be arranged adjacent the exterior wall of the cup.

What I claim is—

1. A goggle eye-cup having a front window, a wall ventilating opening, and a baffle plate for said opening spaced away from the wall of the cup and overlapping the edge of the opening.

2. A goggle eye-cup having a front window, a wall ventilating opening, and a separately formed baffle plate for said opening attached to the wall of the cup and overlapping the edges of the opening.

3. A goggle eye-cup having a front window, a wall ventilating opening, and a separately formed baffle plate for said opening having a hollow apertured shank portion secured in the latter.

4. A goggle-cup having a front window, a wall ventilating opening, and a separately formed interiorly located baffle plate for said opening secured to the cup.

5. In combination with an eye-protector 110

cup having a front window and a wall ventilating opening, a baffle-plate device having a shouldered hollow shank portion insertible into said opening, and means for retaining 5 the inserted device.

6. An eye-protector cup for a beveled-edge lens, having a front window opening, a lens-edge contacting flange and an inclined

retaining-ring offset forming between them a lens-edge receiving recess, and a spring 10 retaining ring engaging between said inclined offset and the beveled edge of an inserted lens.

In testimony whereof I affix my signature.

FREDERICK WILLSON.
